UNITED STATES PATENT OFFICE

ALBERT NAU-TOURON, OF GRASSE, FRANCE

TEXTILE APPARATUS

Application filed February 8, 1930, Serial No. 426,890, and in France February 7, 1929.

The present invention relates to a method and apparatus for producing a spool of textile threads on a rotating spindle.

One of the objects of the invention is to provide means for winding a spool of textile threads or fibers on a rotating spindle at maximum speed, constant tension, and under easily controlled and varied conditions.

Another object is to provide means for varying the value of the ratio $t:T$, where t =the thread tension known to French spinners as "ballon" and T =the so-called "tangent" tension.

A further object is to provide means for eliminating the frictional electrical effects produced during spinning.

An additional object is to provide a method for eliminating deleterious electrical effects during spinning.

Still further objects will appear in the course of the detailed description now to be given with reference to the accompanying drawings in which:

Fig. 1 shows diagrammatically, the various tensions exerted on the thread, fiber or cord being spun;

Fig. 2 represents an elevation partially in section, of one constructive embodiment of the invention;

Fig. 3 is a plan view of the structure shown in Fig. 2;

Fig. 4 is an elevation, partially in section, of the structure represented in Fig. 2;

Fig. 5 illustrates, in plan, the structure shown in Fig. 4;

Fig. 6 is a diagram showing how tension on the thread varies;

Fig. 7 is a section taken on line 7—7, Fig. 2, showing an electrical neutralizing device.

Referring to Figs. 1 to 3 and 7 of the drawings, there is shown a rotatable spindle 1 upon which a spool of thread 2 is to be wound, a thread 3 adapted to be wound on spool 2 and whose tension is to be controlled and

regulated, a plate 5 provided with any standard means (not shown) for being reciprocated back and forth in parallel to the axis of spindle 1,—a pulley 6,—a ball-bearing 7 supporting elements 5 and 6 in rotatable relation to one another,—a cable 9 anchored at one end to element 5 and frictionally embracing a predetermined arc of groove 8 in pulley 6,—a weight 10 regulating the tension of cable 9,—a tapering shell 11 threadedly engaging with pulley 6 and provided with (a) a plurality of orifices 13 traversing a flange 12 formed thereon, (b) an orifice 16 permitting thread 3 to pass successively through orifices 13 and 16 onto spool 2 and (c) slots 17 and 18 permitting orifices 13 and 16 to be easily threaded,—a fixed or movable guide 14 for directing thread 3 from cylinders 4 towards an orifice 13 and positioned in line with spindle (Fig. 1) and means for neutralizing or discharging electricity generated by the frictional contact of thread 3 with orifices 13, 16 and exterior surface 15 of shell 11 comprising either (x) a lever 22 pivoted at 23 and having a thickened extremity 27, a lining 28 adapted to polish thread 3 moving thereunder, an abutment 26, a grounded wire 39 for leading off the electricity generated and a spring 24 forcing lever 22 in direction 25 or (y) a flexible arm 29, lined at 28 to polish the thread moving thereunder and rigidly supported at 30, and a grounding wire 39 or (z) a coating or radioactive material covering surface 15 or flange 12.

The operation of the hereinabove described assembly is practically self-evident. Thread coming from a cylinder passes through guide 14 in line with spindle 1, then through an orifice 13 over surface 15 into orifice 16 and onto spool 2, assemblies 22, 23, 24, 26, 27, 28, 39 or 28, 29, 30, 39 or their radioactive equivalents serving to discharge the electricity developed by friction. By varying the lateral

position of the orifice 13 chosen relatively to orifice 18 any desired ratio of

$\frac{t}{T}$

5 may be obtained, where t = the thread tension known to French spinners as "ballon" and T represents the tangent tension (see diagram Fig. 1). By varying the angle of torsion α 10 (i. e. the angle between orifices 13 and 18 in directions 20 or 21), the ratio

$\frac{t}{T}$

15 may be further modified (see Fig. 2). The elements represented in Figs. 4 and 5 are designed to permit both variation of angle α and the length of the trajectory between orifice 13 and 18. Here, element 11 in the assembly 20 represented in Figs. 2, 3 and 7 is replaced by a shell 31 threadedly engaging with pulley 6 and telescopically engaging with an exteriorly tapered extension 33 forming a driving fit therewith. A slide 35 adjustably 25 mounted on flange 34 of extension 33, and having an orifice 13 and a slot 17 formed therethrough permits orifice 13 to be displaced to form any angle α desired with an orifice 16 traversing shell 31 and a second adjustable 30 slide 36 permits the rotating assembly to be balanced for any position of slide 35. To facilitate the threading of orifice 16 a slot 18 is formed in telescoping shells 31 and 33 and to maintain an alignment for relative 35 longitudinal displacements of the latter, there is provided a pin 38 rigidly attached to shell 31 and slidably guided on an elongated slot 37 traversing shell 33.

The mode of operation of this form of device is very simple. To vary angle α , slide 35 is displaced and held in position either by (a) mounting the latter so as to have a driving fit with flange 34 or (b) slide 35 or flange 34 or both which are magnetized so as remain 45 fixed in any position of adjustment. To vary the length of the thread spiral extending between orifices 13 and 16, shell 33 is displaced telescopically over shell 31 to vary the vertical distance between flange 34 and orifice 16 50 as desired. Fig. 6 shows how for a given angle as seen from Figs. 4 and 6, 90° is the maximum limit for angles Ba and Bb or their complements Oa and Ob representing the inclination of thread 3 so that spiral thread 55 lengths $1a$ and $1b$ may be varied by varying height between the limits Ha and Hb . The shell 33 does not necessarily have to form a driving fit with shell 31 for, if either the former or the latter, or both are formed of 60 ferrous metal and magnetized, they will remain in any position of relative adjustment.

The invention is not to be taken as limited to the particular form structure shown in any single figure; thus, elements 35 and 36 65 (Figs. 4 and 5) may be replaced by a plu-

rality of holes 13 traversing a flange 12 as shown in Fig. 2 and conversely.

What I claim is:

1. In a textile machine, a rotatable spindle,—a shell rotatably mounted outside said spindle, said shell having a pair of orifices formed therein spaced from one another in the direction of the length of said spindle, and means for rotating said spindle, said shell having an elongated slot formed therein extending from one of said orifices to one of the peripheral edges of the shell, whereby a thread may be moved along said slot into said last named orifice. 70

2. In a textile machine, a rotatable spindle,—means for rotating said spindle,—and a shell positioned outside said spindle, said shell having a pair of orifices formed therein spaced from one another both in the direction of the length and in the direction of rotation of said spindle, said shell having an elongated slot formed therein extending from one of said orifices to one of the peripheral edges of the shell, whereby a thread may be moved along said slot into said last named orifice. 80

3. In a textile machine, a rotatable spindle,—means for rotating said spindle,—a rotatable shell positioned outside said spindle and having a pair of orifices formed therein spaced from one another both in the direction of the length and in the direction of the rotation of said spindle, said shell having an elongated slot formed therein extending from one of said orifices to one of the peripheral edges of the shell, whereby a thread may be moved along said slot into said last named orifice. 90

4. A structure as defined in claim 3 in combination with means for exerting a braking action on the rotation of said shell. 100

5. In a textile machine, a rotatable spindle,—means for rotating said spindle,—an extensible shell rotatably mounted outside said spindle, said shell having an orifice formed therethrough,—and thread guiding means mounted on said shell in angularly adjustable relation to said orifice. 110

6. A structure as defined in claim 5, in combination with means mounted on said shell for counterbalancing said guiding means. 115

7. In a textile machine a rotatable spindle,—means for rotating said spindle,—a pair of shells telescopically slidably with relation to one another and rotatably mounted outside said spindle, one of said shells having an orifice formed therethrough,—and thread guiding means mounted on said shell and spaced from said orifice in both the direction of the length and the direction of rotation of said spindle. 120

8. In a textile machine a rotatable spindle,—means for rotating said spindle,—and an extensible shell rotatably mounted outside said spindle, said shell having an orifice formed therethrough,—and thread guiding 130

means mounted on said shell and spaced from said orifice both in the direction of the length and in the direction of rotation of said spindle.

5 9. A structure as defined in claim 7 wherein one of the pair of shells is magnetized for retaining said shells in a fixed telescopic position as and for the purpose described and specified.
